UNITED STATES PATENT OFFICE

2,512,828

SPEAKER'S STAND

Fred V. Collins, Des Plaines, Ill., assignor to
William F. Stahl, Kenilworth, Ill.

Application September 11, 1948, Serial No. 48,882

4 Claims. (Cl. 88-24)

1

This invention relates to an improved speaker's stand.

Speakers' stands have remained substantially unchanged and unimproved for centuries; a typical speaker's stand consists simply of a pedestal equipped at its top with a flat table, usually inclined slightly, on which the speaker can place his notes or other reference material.

One of the major drawbacks of a conventional speaker's stand is the fact that it provides the speaker with no convenient means of depositing and using the notes for a lengthy speech. As a rule the speaker's notes must be written or typed onto a series of sheets, and as the speech is delivered the speaker must shuffle the pages and, frequently, must give close attention to them in order to read the small written or printed characters thereon.

This procedure is objectionable because it makes it obvious to listeners that the speech is being read; a packet of shuffled notes is undesirable for the additional reason that they are very likely to become disarranged or some sheets may be lost.

In recent years, an increasing number of ministers, lecturers, and other public speakers have preferred to use a public-address system employing an electronic amplifier. Such a system permits a speaker to reach a large audience without unduly straining his voice. Moreover, by assuring everyone in the audience that he will be able to hear clearly, a public-address system assists a speaker greatly both in drawing crowds and in holding their attention.

Public-address systems have in the past often been built into lecture halls, churches, and auditoriums as integral parts of the structure. For use in halls not so equipped, portable public-address systems have been available, but have not been entirely satisfactory. In making a temporary installation of a portable system, some means must be used for supporting one or more loud speakers, and frequently no satisfactory place of concealment for the amplifier chassis is available. Thus the net result is frequently an unsightly array of loud speakers, electronic devices, and connecting cables.

This invention has been directed to the solution of the practical problems just described which beset public speakers; the resulting structure is a speaker's stand having many improvements and advantages not heretofore found in such devices.

An object of this invention is to provide a speaker's stand wherein the speaker's lecture

2

notes may be presented before him in proper sequence without the necessity for his handling individual sheets of notes.

Another object of this invention is to provide a speaker's stand in which the subject matter of the speaker's lecture notes can be read by him from his normal standing position, without the necessity for his bending over or otherwise drawing attention to the notes.

Still another object of this invention is to provide a speaker's stand wherein the notes for a lengthy lecture can be stored within the stand and passed in proper sequence before the speaker's eyes without the necessity for manual handling thereof by the speaker.

A still further object of this invention is to provide a speaker's stand having built therein, as an integral part, a public-address microphone and amplifier.

Still another object of my invention is to provide a speaker's stand combining a complete portable public-address system with apparatus for projecting before the speaker's eyes a magnified image of his lecture notes.

Other objects and advantages of my invention will appear as the specification proceeds.

The invention is illustrated, in a preferred embodiment, by the following drawings, of which Figure 1 is a view in perspective of a speaker's stand made according to my invention, and Fig. 2 is a semi-diagrammatic view, partly in section, of the speaker's stand of Fig. 1.

In the drawings, the reference numeral 10 denotes a cabinet or housing which may be shaped somewhat like a conventional pulpit, with a slanted top portion as shown. Preferably cabinet 10 may carry a plurality of casters 21, to facilitate its being moved about from place to place. In the rear side of the cabinet a pair of doors 11 and 12 are provided to permit convenient access to the interior.

The slanting table-like portion of cabinet 10 contains a translucent screen 13, which may be made of ground glass or other material having similar translucent properties.

On the horizontal table portion of cabinet 10 I have provided a microphone 14, mounted on an upright shaft 15.

Within the interior of cabinet 10, as shown in Fig. 2, I have provided a pair of rollers or reels denoted respectively 16 and 17. Reels 16 and 17 are carried respectively on shafts 16a and 17a, which are suitably supported by the side walls of cabinet 10. In the embodiment shown, I have arranged reel 17 anterior to and above reel 16,

so that a sheet 18 of paper, parchment, or other material stretched between the two reels occupies a plane at an acute angle from the horizontal and substantially parallel to the plane containing screen 13.

Reel 16 is equipped with a clutch member 19 which is in turn linked by belt 22 to a foot pedal 23. Foot pedal 23 is pivoted at one end to a pivot shaft 24 carried on a bracket 25 rising from and affixed to the floor of cabinet 10. The other end of pedal 23 extends outward through the rear wall of cabinet 10 to a point, as best shown in Fig. 1, where it is conveniently available for operation by the right foot of a speaker standing behind the speaker's stand. Clutch 19 may be of any conventional sort adapted to carry reel 16 with it when turned in one direction and to release reel 16 when turning in the opposite direction. As shown in Fig. 2, clutch 19 is adapted to turn reel 16 with it when clutch 19 is rotated counter-clockwise. A shelf 26, extending between and supported by the side walls of cabinet 10, serves as a guide for an elongated sheet 18 of paper, cloth, or parchment extending between the reels 16 and 17.

A pair of lamps 21 are supported by any convenient means (not shown) within cabinet 10 in a position where they can illuminate the upper surface of sheet 18.

A lens optical system 28 is positioned between sheet 18 and screen 13 where it is adapted to throw onto screens 13 a magnified image of a portion of sheet 18.

An electronic amplifier 29 is carried on the floor of cabinet 10, and a loud speaker 30 is mounted on the front upright wall of cabinet 10, where it will be effective to transmit sound outward toward the audience.

While the wire connections between microphone 14, amplifier 29, and loud speaker 30 are not shown in the drawings, it will be understood that microphone 14 is connected to the input terminals of amplifier 29, while loud speaker 30 is connected to the output terminals thereof. Any convenient means, such as power socket 31, may be provided for supplying electrical energy to amplifier 29 and loud speaker 30.

Operation

In the operation of my invention, a speaker will have his notes written, printed, or typewritten on a single long sheet of paper. If preferred, the notes can be made up on sheets of normal size and they may then be affixed together with tape or other adhesive to form an elongated sheet. Preferably enough blank paper to extend between reels 16 and 17 should be left at the top of the manuscript. It is then rolled up onto reel 17 and the free end of the sheet is suitably clipped or otherwise affixed to reel 16. This will result in the text of the notes being displayed on the sheet upside down; a reversal of orientation will take place in the convex lens system 28 and as a result an enlarged image of the text material, right side up, will appear on screen 13.

As the lecturer proceeds with his address, he will advance position of reel 16 by actuating foot pedal 23 each time he has covered all the note material within his view. The microphone and public-address system will, of course, operate effectively to carry his words to the audience. It will be noted that in this invention the microphone, loud speaker, and screen projection system cooperate to permit the speaker to employ to the fullest extent his skill at delivery, since

he is relieved of the necessity for speaking unduly loud, he is provided at all times with full notes, or verbatim text if desired, without handling or shuffling notes, and so far as the audience can detect he delivers his speech from memory or extemporaneously.

If the lecturer is accustomed to delivering at intervals a series of set speeches, reel 17 may be made detachable and a large number of spare reels carried, each spare reel containing the notes for a particular speech. A suitable storage rack for such spare reels may readily be provided within cabinet 10.

It will be understood that after the completion of a speech the notes therefore should either be removed from the reels or, if desired re-wound onto reel 17. Any suitable means (not shown) permitting the temporary release of clutch 19 may be provided to permit reel 16 to turn in the reverse direction to permit re-winding of sheet 18 onto reel 17.

While I have in this specification described in detail one embodiment of my invention for purposes of illustration, it will be understood that many changes in detail and arrangement of parts may be made by those skilled in the art without departing from the spirit of my invention.

I claim:

1. A speaker's stand comprising a cabinet, a reel adapted to carry and hold for display an extended sheet of notes, clutch means affixed to the reel, a foot pedal, linkage coupling from foot pedal to the clutch adapted upon actuation of the foot pedal to advance the sheet of notes, electronic amplifier means mounted within the cabinet, and a microphone carried by the cabinet and adapted to be coupled to the input of the amplifier.

2. A speaker's stand comprising a cabinet, a reel adapted to carry and hold for display an extended sheet of notes, clutch means affixed to the reel, a foot pedal, linkage coupling the foot pedal to the clutch adapted upon actuation of the foot pedal to advance the sheet of notes, electronic amplifier means mounted within the cabinet, a microphone carried by the cabinet and adapted to be coupled to the input of the amplifier, and a loud speaker carried by the cabinet and driven by the amplifier.

3. A speaker's stand comprising an enclosed cabinet, a translucent screen mounted in the top of said cabinet, a reel carried within the cabinet adapted to hold for display and to advance an extended sheet of notes, a light source within the cabinet for illumination of said sheet, a lens positioned intermediate said sheet and said screen, clutch means coupled to said reel, a foot pedal, linkage coupling the foot pedal to the clutch means operative to advance said sheet on actuation of the foot pedal, an electronic amplifier carried within the cabinet, and a microphone mounted on said cabinet and adapted to be coupled to the input of said amplifier.

4. A speaker's stand comprising an enclosed cabinet, a translucent screen mounted in the top thereof, a reel adapted to hold for display and to advance an extended sheet of notes, a light source within the cabinet for illuminating said sheet, a lens positioned within the cabinet intermediate the sheet and the screen, clutch means coupled to the reel, a foot pedal, linkage coupling the foot pedal to the clutch means adapted to advance the sheet upon actuation of the foot pedal, an electronic amplifier mounted in said cabinet, a microphone carried by said cabinet and adapted to be coupled to the input of said

5

amplifier, and a loud speaker mounted in the forward wall of said cabinet and adapted to be driven by said amplifier.

FRED V. COLLINS.
